(57) **CLAIM**

We claim, the ornamental design for a lamp, as shown and described.

DESCRIPTION

FIG. 1 is a perspective view of the lamp;
FIG. 2 is a top view of the lamp;
FIG. 3 is a bottom view of the lamp;
FIG. 4 is a left side view of the lamp;
FIG. 5 is a right side view of the lamp;
FIG. 6 is a front view of the lamp; and,
FIG. 7 is a back view of the lamp.

The break lines indicate that the appearance of any portion of the lamp between the break lines forms no part of the claimed design.
